UNITED STATES PATENT OFFICE.

FRANK WALKER, OF LOS ANGELES, CALIFORNIA, ASSIGNOR TO WILLIAM LLEWELLYN,
OF LOS ANGELES, CALIFORNIA.

AUTOMATIC FLUSH-TANK.

1,271,813.

Specification of Letters Patent.

Patented July 9, 1918.

Application filed August 4, 1914. Serial No. 855,065.

To all whom it may concern:

Be it known that I, FRANK WALKER, a citizen of the United States, residing at Los Angeles, in the county of Los Angeles and 5 State of California, have invented new and useful Improvements in Automatic Flush-Tanks, of which the following is a specification.

This invention relates to that class of 10 flush tanks in which a siphon is started into operation by the water rising to a determined height in the tank.

An object of this invention is to make the 15 operation of the siphon more certainly positive or immediate so as to invariably supply a full volume of water initially to flush the sewer. That is to say, it is desirable that the flushing water shall always, at each operation, act in the sewer suddenly and in 20 great volume rather than by gradual increase from a small to a full volume, which gradual increase could cause a constant leakage of the siphon and thus make it wasteful and unreliable in its operation.

An object of this invention is to accomplish that result and this is done by so 25 directing the compressed air trapped in the descending limb of the siphon, that it will without fail, act to suddenly and completely 30 blow out the water seal of the air vent limb of the siphon, thus allowing sudden escape 35 of the compressed air trapped in the descending limb of the siphon; such escape occurring while the main body of the seal 40 is undischarged, so that practically the full momentum of the falling body of water entirely filling the descending limb of the siphon will suddenly be applied to expel the water in the ascending limb.

The accompanying drawings illustrate 45 the invention.

Figure 1 is a vertical mid-section of a sewer flush tank constructed in accordance with this invention, the water being represented as approaching the flushing stage.

Fig. 2 is a view looking into the dome from below, the dome being removed from the intake limb of the siphon.

Fig. 3 is a plan section of the siphon on 50 line x^3 , Fig. 1.

The dome 1 is inverted over the descending limb 2 which communicates with the vertically ascending air vent limb 3 and the likewise ascending discharge limb 4.

The dome is of the usual construction excepting that the guard 5 for the seal-breaking vent 6 has a flush vent 7 in its bottom so that during the flushing operation a current of water will pass up through the portion of the guard chamber which is below 60 the level of the seal-breaking vent, thus to prevent the guard chamber from filling up by rust and corrosion which has heretofore resulted in closing the seal-breaking vent, the purpose of the vent 7 being to allow a 65 flow of water to wash out the bottom of the seal-breaking vent guard chamber to prevent accumulations and to keep the seal-breaking vent open.

The main feature of the present invention 70 consists in the construction of the air vent limb 3 which communicates with the main outlet channel or ascending limb 4 and the lower end of the descending intermediate limb 2 just above the level of the sealing 75 bend which is in the form of a bridge 8 for the compressed air from the descending limb 2 to act at first immediately upon only a comparatively small cross-sectional area 80 at the bottom of the water column in the air vent limb 3, and thus to concentrate the force of the compressed air so that in practice when the compressed air passes the bottom of the partition 9 between the descending limb 2 and the air vent limb 3, it will 85 blow out the whole column of water standing in the air vent limb 3, practically at the instant of starting; the compressed air expanding entirely across the air vent limb 3 above the bridge 8; and being followed up 90 by the great body of compressed air driven down through the descending limb by the weight of the water falling in said limb, and expelling practically the entire liquid contents of the air vent limb, and instantly and 95 completely clearing the air vent passage so that the air pressure in the siphon is reduced to atmospheric pressure so that there is practically no obstruction to the sudden falling of the water body from the dome 100

through the descending limb 2 in such volume as to practically fill said descending limb at once; there being a sheer unobstructed drop from the top of the descending limb to the bottom thereof to drive the water out of the ascending discharge limb 4 of the siphon, which, up to this time has remained full. The air vent limb also acts as outlet for the liquid precipitated into it 10 through limb 2.

Preferably the bridge 8 terminates in an upwardly projecting lip 10 that extends from side to side of the air vent limb 3 at the bottom of said limb, said bridge being 15 a rounded continuation of the partition 9 between the descending limb 2 and the air vent limb 3, and the upwardly extending lip directing the air up under the column of water in the air vent limb 3 so that the action of the compressed air lifts and drives 20 the water out of the air vent limb suddenly in the manner just described. Said water flows from the air vent over the top of the ascending discharge limb 4 thus momentarily increasing the depth of the water in limb 4 thereby tending to obstruct any discharge of water through limb 4 until the impetus of the full column of water falling 25 through limb 2 onto the water at the bottom of limb 2 becomes effective to suddenly drive out the water in limb 4.

In this way I have made it certain that there will be no leakage from the seal and that the flushing will be effected by a sudden rush with practically no preliminary gentle flow.

The passages through the siphon are rectangular, preferably oblong in transverse section, as shown in Fig. 3, and the bridge 40 is rounded on its under side to allow the water to flow unobstructedly to the narrow slot formed between the upwardly extending lip 10 and the partition 11.

In the drawings *a* represents the reservoir flushing tank, *b* the gradual water supply, *c* the sealing bend of the trap, *d* the initial terminal of the partition 11 at the bottom of the descending intermediate limb 2 of the siphon, *e* the throat or reduced passageway and *f* the outlet into the sewer 12.

The dome 1 like the bells or domes heretofore used in flush tank siphons is removable from the intake end of the intermediate limb 2 and the intermediate limb 2 is unobstructed from top to bottom and the initial terminal *d* of the partition 11, which partition divides the lower end of the descending intermediate limb and also the seal into the two limbs or channels 3 and 4, is close to 55 the level of the bridge or bend 8, so that an instrument may be inserted down through the intermediate limb 2 and through the initial end of the air vent 3 to

scrape off accumulations of rust which may occur in the throat *e*.

65

The comparatively great depth of the column of liquid in the channel 4 causes all of the air pressure produced by the column of liquid in the reservoir *a* to be effective on the initial surface of the column of liquid 70 in the channel 3, and in practical operation the body of liquid in the narrow throat *e* holds back the air, while the bend 8 is comparatively short in order to minimize capillary attraction and the formation of air 75 bubbles; and whenever air flows around in contact with the lip 10 it is delivered at the center of the column in the channel 3 where it expands equally toward both the walls 9 and 11 as above set forth, thus becoming 80 immediately effective to lift the water in 3 and to start the siphon.

I claim:

In an automatic flush tank, a siphon provided with a vertically descending limb having integrally joined thereto at the lower part of one of its walls a vertically ascending limb, said wall thus being common to both limbs; an outlet in communication with the upper part of the ascending limb; a curved part connecting the lower ends of said limbs and together with the ascending limb forming the seal of the siphon; a partition beginning within the descending limb at a level slightly above the level of the 95 lower end of the common wall and extending from side to side of the siphon; said partition also being provided with a curve and having a terminal ascending vertically within the ascending limb to the level of the 100 outlet; said partition thus dividing the lower end of the descending limb and also dividing the seal into two channels, each channel having a vertically ascending passage therein; said passages terminating at 105 the same outlet level; and one of the channels having a curve within and above the curve of the other channel so that the depth of the first-named channel is less than the depth of the last-named channel; a terminal bend in said common wall extending upwardly into the vertically ascending passage 110 of the first-named channel and reaching from side to side of the siphon; said bend being comparatively short and constituting the upper part of the curve in the first-named channel so that capillary attraction and the formation of air bubbles are thereby minimized, and also producing a throat or reduced passageway at the lower end of the vertically ascending passage in the first-named channel; and the passage in the first-named channel assuming its full width immediately above the terminal of said bend 115 so that the air entrapped in the descending limb of the siphon may suddenly expand 120

125

above said bend at a predetermined moment and blow out the liquid seal in the first-named channel, while the weight of the column of liquid in the last-named channel is 5 normally sufficient to resist the pressure of the entrapped air, and the main body of the liquid seal is thus retained in the last-named channel.

In testimony whereof, I have hereunto set my hand at Los Angeles, California this 10 30th day of July, 1914.

FRANK WALKER.
